ABSTRACT OF THE DISCLOSURE

A safe space heater is adapted to receive replaceable containers of semisolid fuels such as thickened kerosene, gasoline, diesel oil, etc. The heater includes a fuel feed system and valve system whereby the supply of fuel is automatically regulated and the fuel supply is cut-off in the event of tip-over of the heater. The heater reduces the hazards associated with space heaters utilizing liquid fuels.

This invention relates to a safe space heater, and more particularly to an apparatus for supplying semisolid petroleum fuel to a combustion zone. The invention especially relates to a safe space heater which is useful for heating and cooking and which is adapted to receive replaceable containers of semisolid petroleum fuels such as thickened kerosene, gasoline or diesel oil. In another aspect, the invention relates to a replaceable fuel cartridge for semisolid petroleum fuel.

In view of their poor safety record, kerosene space heaters have been banned in many states and in some areas all liquid petroleum fuels have been included in this restriction. The hazards resulting from the use of liquid petroleum fuels may be attributed primarily to flooding of the burner firepot or tipover of the burner. Solid fuels have the disadvantage that they must be hand stoked in these types of heaters. It is the primary objective of this invention, therefore, to provide a space heater which is not subject to the limitations and disadvantages of space heaters which have been available heretofore.

It is a further object to provide an apparatus for supplying semisolid petroleum fuel to a combustion zone.

It is still a further object to provide a replaceable fuel cartridge which is adapted to be placed within the fuel feed system of a safe space heater.

Broadly, the space heater of the present invention comprises a fuel container having an outlet orifice, means for discharging semisolid petroleum fuel through the outlet orifice, regulating means operatively connected to the outlet orifice so that the supply of semisolid fuel discharged from the container may be regulated, and a combustion zone communicating with the regulating means.

The invention will be better understood by reference to the following detailed description when considered in conjunction with the accompanying drawings illustrating selected embodiments thereof, in which:

FIGURE 1 is a side view, partly in section, of an apparatus for storing and supplying semisolid petroleum fuel to a combustion and heating zone; and

FIGURE 2 is a cross-sectional view of a thermally operated proportionate control valve which may be used to regulate the supply of fuel delivered to the combustion zone.

FIGURE 3 is a perspective cross-sectional view of a suitable disposable fuel cartridge.

FIGURE 4 is a schematic diagram of a thermocouple system which may be used in conjunction with a valve so as to prevent the discharge of fuel in the event of tip-over of the heater.

Referring now more particularly to FIGURE 1, there is shown generally at numeral 10 a heating zone operatively connected to a fuel supply system which is shown generally at 12. The heating zone used herein is of the conventional type and of itself does not form any part of the basic invention.

The fuel supply system shown generally at 12 comprises outer casing 14 supported by a frame including frame members 16 and having an outlet, orifice 18, which directs fuel from cartridge 20 into a means for regulating the fuel supply delivered to the heating zone. This regulating means may be of any approved type, the specific construction not being particularly concerned with the present invention. Here for illustrative purposes is shown a thermally operated proportionate control valve 22 which regulates the fuel supply sent through outlet conduit 24 which is cooperatively connected to the burners (not shown) disposed within the heating zone of the space heater. To limit the amount of fuel delivered to the heating zone, valve 22 (shown in FIGURE 2) is provided with a temperature responsive means, e.g., bellows 48, which actuates valve stem 50 which contacts diaphragm 52 disposed within valve body 54. In the event the diaphragm fails, leakage through the valve may be prevented by means of an auxiliary seal, e.g., O ring 56. Across the top of the bellows may be located a bellows support bar 58 which fits into thread 60 and supports the bellows-valve stem unit. Support mount 62 having groove 69 may be rotated by hand, while the bellows-valve stem combination is prevented from rotating by pin 64 which is fixed in the valve stem and rides in vertical slot 66 located in supported bracket 68. Pin 70 extends through the wall of bracket 68 and contacts groove 69 so that support mount 62 is restrained from vertical movement. Rotation of the support mount 62 raises and lowers the stem position thereby fixing the temperature at which the valve is fully closed. As the desired room temperature is approached, the valve restriction increases and the fuel flow decreases, thereby achieving proportional control.

To maintain a pilot light in heating zone 10 and to prevent the discharge of fuel in the event of burner tip-over, the regulating means is provided with valve 26 which permits a small continuous flow of fuel to be sent through conduit 28 and directs the major proportion of the fuel supply to valve 22. Valve 26 is operatively connected to electrical conduit 30 which includes an activating means (FIGURE 4) communicating with the pilot light zone (not shown) and arranged so that valve 26 is automatically closed when the pilot light goes out or when the heater is tipped over. This may be accomplished, for example, by a thermocouple activated magnetic valve of the type used in conventional heaters for pilot light control. Referring to FIGURE 4, it is seen that the activating means may comprise thermocouple wires 31 and 33 which are joined at junction 29 located in the pilot light zone to thereby produce electrical energy which via electrical conduit 30 maintains valve 26 in the open position. Segments of thermocouple wire 33 are joined by means of mercury switch 27 which is arranged to break the electrical circuit in the event of tipover of the space heater thereby resulting in automatic closure of valve 26. For added safety, outlet conduit 24 includes a heat dissipation means, e.g., cooling fins 32, for preventing excessive conduction of heat from the combustion zone to the semisolid fuel, thereby substantially maintaining the consistency of said fuel.

One end of the outer casing is open ended and is adapted to be engaged with removable cover 34 by a seuring means which may be, for example, wing nut assembly 36. Removable cover 34 comprises movable presser plate 38 connected to rod 40 which is slidably

disposed within the cover and is used for withdrawal of the presser plate from the cartridge. Removable cover 34 also includes means for applying a force on the presser plate to move said plate and rod in the direction towards the outer casing outlet. The force means herein utilized for such purpose may be a resilient means, e.g., helical spring 42, for urging the presser plate against diaphragm 44 which is disposed within the cartridge. Diaphragm 44 which rests upon fuel 46 forms a substantially fuel-tight seal with the side walls of the cartridge and is adapted to slide within the body of said cartridge towards the outlet orifice when acted upon by the presser plate.

A suitable fuel cartridge may be, for example, the cylindrical container shown in FIGURE 3. The cartridge is shown having side walls 70 and end walls 72 and 74. The end wall 72 has an outlet orifice 76 provided with removable closure 76. End wall 74 is of the strippable type which may be readily hand removed by tearing off side wall segment 78. Disposed within the cartridge between closed end 74 and the fuel is diaphragm 80 which forms a substantially fuel-tight seal with the side wall. The diaphragm is adapted to slide within the body of the cartridge and is restrained from moving out of the cartridge by crimp 82.

With the parts constructed as described, the operation is as follows: fuel cartridge 20 having orifice closure 76 and end 74 removed is inserted into outer casing 14 so that cartridge outlet orifice 76 is in alignment with the outlet opening of the outer casing to thereby permit discharge of the fuel from the cartridge. Cartridge 20 is then secured in place by cover 34 which is mechanically interlocked with outer casing 14 by wing nut assembly 36 and arranged so as to draw presser plate 38 against diaphragm 44 of cartridge 20. Helical spring 42 mounted around rod 40 of cover 34 and disposed between the cover top and presser plate exerts a substantially constant force upon presser plate 38 which in turn exerts the force on diaphragm 44 and thence on fuel 46. Thermally operated proportionate control valve 22, which communicates with casing 14 and fuel supply conduit 24, regulates the admission of fuel 46 to the combustion zone. During operation of the apparatus, presser plate 38 acts upon cartridge diaphragm 44 so as to force the fuel in the cartridge through the outlet orifice, past the control valves and thence into the pilot light and burner feed lines. Control valve 22 is adjusted so that a minimum quantity of fuel, sufficient only to maintain the required level of fuel in the burner pot, is delivered to the combustion zone, thereby maintaining the desired area temperature.

The semisolid fuel used herein may be any of the conventional gelled or grease-like hydrocarbon fuels which require a starting pressure to initiate their flow. Typically, these fuels comprise, for example, admixtures of gasoline, kerosene or distillate fuel oil with thickening agents such as soaps, polymeric and inorganic thickeners, and the like. Such fuel compositions are well known in the art and specific examples thereof may be found, for example, in U.S. Patents 1,262,808 and U.S. 3,114,710 which are incorporated herein by reference.

It is not intended that this invention be limited to the specific examples presented by way of illustration. The scope of the invention is limited only by the appended claims.

What is claimed is:

1. A safe space heater adapted to burn semisolid petroleum fuel which comprises in combination:

- (a) a frame;
- (b) a fuel container supported by said frame, said container having side walls and one end wall having an outlet orifice, said container holding a supply of semisolid petroleum fuel;
- (c) means for discharging said fuel through said outlet orifice;
- (d) a combustion zone including a pilot burner for producing a pilot flame;

(e) a fuel line for delivering semisolid fuel from said outlet orifice to said combustion zone; and

(f) a regulating means positioned in said fuel line so that the supply of fuel discharged from said container may be regulated, said regulating means including a thermocouple-activated magnetic valve, a thermocouple energized by the heat produced by said pilot burner so that said valve is closed upon burn-out of the pilot flame, and a mercury switch positioned in series with said thermocouple so that said valve is closed upon tipover of the space heater.

2. A safe space heater according to claim 1 wherein said regulating means includes a thermally operated proportionate control valve.

3. A safe space heater adapted to burn semisolid petroleum fuel which comprises in combination:

- (a) a frame;
- (b) a fuel container supported by the frame, said container having side walls and two end walls, one of said end walls having an outlet orifice, said other end wall including a pressure plate forming a substantially fuel-tight seal with said side walls and adapted to slide within the body of said container;
- (c) means for applying a force on said pressure plate to move said plate toward said outlet orifice to thereby discharge said fuel through said outlet orifice;
- (d) a combustion zone including a pilot burner for producing a pilot flame;
- (e) a fuel line for delivering semisolid fuel from said outlet orifice to said combustion zone; and
- (f) a regulating means positioned in said fuel line so that the supply of fuel discharged from said container may be regulated, said regulating means including a thermocouple-activated magnetic valve, a thermocouple energized by the heat produced by said pilot burner so that said valve is closed upon burn-out of the pilot flame, and a mercury switch positioned in series with said thermocouple so that said valve is closed upon tipover of the space heater.

4. A safe space heater according to claim 3 wherein said regulating means includes a thermally operated proportionate control valve.

5. A safe space heater adapted to burn semisolid petroleum fuel which comprises in combination:

- (a) a frame;
- (b) an outer casing supported by the frame, said outer casing having side walls and one end wall, said end wall having an outlet opening;
- (c) a fuel cartridge disposed within said outer casing, said cartridge containing semisolid petroleum fuel and having side walls and two end walls, one of said end walls having an outlet orifice in alignment with the outlet opening of said outer casing, said other end wall including a diaphragm forming a substantially fuel-tight seal with said cartridge side walls and adapted to slide within the body of said cartridge;
- (d) means for urging said diaphragm in the direction toward said outlet orifice to thereby discharge fuel through said outer casing outlet;
- (e) regulating means operatively connected to said outer casing outlet so that the supply of fuel discharged from said cartridge may be regulated; and
- (f) a combustion zone communicating with said regulating means.

6. A safe space heater according to claim 5 wherein said regulating means includes a thermally operated proportionate control valve.

7. A safe space heater according to claim 6 wherein said combustion zone includes a pilot burner for producing a pilot flame and said regulating means includes a thermocouple activated magnetic valve, a thermocouple energized by the heat produced by said pilot burner so that said valve is closed upon burn-out of the pilot flame

and a mercury switch positioned in series with said thermocouple so that said valve is closed upon tipover of the space heater.

8. A safe space heater adapted to burn semisolid petroleum fuel which comprises in combination:

- (a) a frame;
- (b) an outer casing supported by the frame, said outer casing having side walls and one end wall, said end wall having an outlet opening;
- (c) a fuel cartridge disposed within said outer casing, said cartridge containing semisolid petroleum fuel and having side walls and two end walls, one of said end walls having an outlet orifice in alignment with the outlet opening of said outer casing, said other end wall including a diaphragm forming a substantially fuel-tight seal with said cartridge side walls and adapted to slide within the body of said cartridge;
- (d) a removable cover for said outer casing, said cover including means for securing said cover to said outer casing, a presser plate for contacting said diaphragm, resilient means for urging said pressure plate against said diaphragm in the direction toward said outlet orifice to thereby discharge fuel through said outer casing outlet;
- (e) regulating means operatively connected to said outer casing outlet so that the supply of fuel discharged from said cartridge may be regulated, said regulating means including a thermally operated proportionate control valve adapted to control the delivery of fuel so that a desired area temperature can be maintained and a thermocouple activated magnetic valve in series with a mercury switch which

causes the closing of said valve upon tipover of the space heater to thereby prevent discharge of fuel; and

- (f) a combustion zone communicating with said regulating means.
